UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

PULLER-MACHINE.

1,189,007.

Specification of Letters Patent. Patented June 27, 1916.

Application filed February 10, 1913. Serial No. 747,551.

To all whom it may concern:

Be it known that I, DUDLEY S. SEYMOUR, a citizen of the United States, residing at Oak Park, in the county of Cook, State of Illinois, have invented certain new and useful Improvements in Puller-Machines, of which the following is a description, reference being had to the accompanying drawing and to the figures of reference marked thereon.

The invention relates to new and useful improvements in puller machines which are adapted to be used in connection with a sewing machine, and which operate in unison with the feed of the sewing machine to exert an intermittent pull or feed on the material being stitched, in order to relieve the strain on the sewing machine feed when operating upon heavy materials.

20 The invention is an improvement upon the puller machine shown and described in my co-pending application, Serial No. 379,218, filed June 15, 1907. In the mechanism shown in the application referred to, the 25 puller wheels are operated by a roller friction clutch, the rollers of which bear directly upon the surfaces of the clutch members. It has been found in practice that in a device of this character the rollers will at times 30 wear grooves in the faces of the clutch members, which prevent the proper clutching of the parts so as to maintain a proper timing between the feed of the puller and the feeding of the sewing machine.

35 An object of the present invention is to provide a clutch mechanism which is so constructed that the clutching rollers rest upon hardened plates so as to avoid the objectionable wear above referred to.

40 In the drawings, which show by way of illustration one embodiment of the invention: Figure 1 is a plan view of a puller and a sewing machine with which it co-operates, the view being taken directly above the 45 work support, and parts being broken away in section to show the manner of operating the puller mechanism from the main shaft of the sewing machine; Fig. 2 is an enlarged detail partly in section and partly in end 50 elevation showing the relation of the feeding mechanism to the puller wheels; Fig. 3 is an enlarged detail partly in section showing the main shaft of the puller mechanism and the clutch members for operating the 55 same; Fig. 4 is a sectional view on the line

4, 4 of Fig. 3; Fig. 5 is a longitudinal sectional view through the clutch members; Fig. 6 is a perspective view of one of the clutch members detached from its operating parts.

60 The puller machine to which my invention is applied consists of a work support 1, and a standard 2 carrying an overhanging arm (not shown), both of which are carried by a supporting bed 3, which is adapted to be 65 attached to and held in fixed relation to the supporting bed 4 of the sewing machine. The sewing machine is provided with a cloth plate or work support 5, and a standard 6 carrying the usual overhanging arm. The 70 main shaft 7 of the sewing machine is mounted in suitable bearings beneath the work support 5, and is operated from the belt wheel 8.

75 The sewing machine is provided with a feed dog 9, which is carried by the usual feed bar 10 pivoted to the feed rocker 11, which is oscillated from the main shaft 7 through an arm 12 which is pivotally connected to an eccentric strap 13, co-operating 80 with the eccentric on the main shaft. This feed dog is raised and lowered by an eccentric 14 also carried by the main shaft 7. Co-operating with the main feed dog 9 is a presser foot 15, which is mounted in the 85 overhanging arm carried by the standard 6.

85 The stitching mechanism is indicated by the needles 16, and may be of any desired character.

90 From the above description it will be apparent that the sewing machine is provided with an intermittently operated feed dog which acts to present the material to be stitched to the stitching mechanism.

95 The work support 5 of the sewing machine and the work support 1 of the puller machine are substantially on the same level, as clearly shown in Fig. 2. Mounted in suitable bearings beneath the work support 1 of the puller machine is a shaft 17 which 100 carries a roller 18 having spaced projections 19. This roller 18 is so proportioned that the projections extend through a slot 20 in the work support 1, and engage the lower face of the material passing over the work support 1. Co-operating with this roller 18 is a roller 21 which is mounted in a suitable head 22 carried by a bar 23 mounted in the overhanging arm 2 of the puller machine. This roller 21 is also formed with spaced 105 110

projections 24, which are adapted to engage the material between the projections 19 on the roller 18. The roller 18 is positively driven and in turn causes the roller 21 to rotate on its bearing. The shaft 17 is intermittently rotated so as to give a surface speed to the roller 18 equally to or slightly in excess of the effective feeding movement of the feed dog 9 of the sewing machine.

As a means for intermittently rotating the shaft 17, I have provided a friction clutch. Rigidly fixed to the shaft 17 is a sleeve 25. This sleeve is bored at the center part thereof so as to fit over the shaft 15 and is locked thereto by set screws 26. At the sides of the center portion of the sleeve are formed enlarged cylindrical recesses 27 and 28. The driving clutch member 29 is in the form of a collar which freely engages the shaft 17, and is supported thereby. This collar at its inner end is formed with three spaced projections 30, the outer faces 31 of which are curved so as to fit freely within the cylindrical recess 27. These projections are practically the same width as the depth of the cylindrical recess. A washer 32 fits the collar 29 and is fixed thereto. This washer is substantially of the same diameter as the sleeve 25 and serves to close the cylindrical recess 27. Between the projections 30 on the collar 29 are cut-away parts forming pockets for the gripping roller 33. The flat surface 34 of the projection 30, above which the gripping roller is located, is provided with a hardened steel wear plate 35, which is secured to the face 34 by suitable screws 36. The roller 33 rests on this hardened plate. It will be understood that there is a recess or pocket 40 between each of the projections 30 and a roller 33 for each pocket or recess. The other face 36a of the projection 30 is bored to form a pocket in which a spring 37 is seated. This spring bears against the roller 33 and forces the same outwardly along the wear plate therefor. The operation of this driving clutch member will be apparent from Figs. 4 and 6. When the driving member or clutch collar 29 is moved in the direction of the arrow as shown in Fig. 4, the roller 33 will at once move outwardly on the wear plate and be forced by the wear plate into gripping contact with the sleeve 25, and thus the sleeve 25 will be caused to move with the collar 29 in the direction of the arrow, as long as said collar 29 is moved in this direction. A movement of the collar 29 in the opposite direction will cause the roller 33 to move inwardly on the wear plate and out of gripping contact with the sleeve 25. This collar 29 is provided with an arm 38 which is clamped thereto, and projects downwardly beneath the shaft 17. The arm at its lower end carries a ball stud 45 which is connected to a link 39. The other

end of the link 39 co-operates with an eccentric on the main shaft 7 of the sewing machine, so that as said shaft is rotated the link 39 will be moved endwise, thus oscillating the arm 38 and, in turn, oscillating the collar 29.

In order to prevent a retrograde or backward movement of the shaft 17, when the collar 29 is moved in a direction opposite to the arrow in Fig. 4, I have provided a holding clutch member 40, which is similar in construction to the driving clutch member 29. Said clutch member 40 is provided with a collar which extends into the cylindrical recess 28 and said collar is formed with projections 30, shaped similar to the projections on the collar 29, and said collars are also provided with wear plates 41, similar to the wear plates 35, and with rollers 42, similar to the rollers 33. The driving clutch and the holding clutch are similarly disposed and, therefore, when the driving clutch is moved so as to cause the rollers to move outwardly on the wear plates and to grip the sleeve and turn said sleeve, the rollers of the holding clutch will be moved inwardly along the wear plates therefor, and out of engagement with the sleeve, and thus permit the sleeve to freely turn. When the driving clutch is moved in the opposite direction, the rollers will be moved out of contact with the sleeve and any tendency of the sleeve to turn in a rearward direction will be prevented by the rollers of the holding clutch engaging the sleeve and preventing any movement of the sleeve, relative to the holding clutch. The holding clutch is fixedly secured to a bracket 43 by suitable screws 44, and the bracket 43 is secured to the base plate 1 of the puller machine by a suitable screw 45. The springs 37 which engage the rollers 33 and 42 force these rollers outwardly along the wear plates, so that the rollers are held in position to at once grip the sleeve when the driving clutch member is moved in the proper direction, or when there is any tendency of the sleeve to move rearwardly relative to the holding clutch, and, therefore, all false movements are prevented. These hardened steel wear plates on which the rollers rest are subject to little wear, and if there should be any wear on the surface contacting with the roller, the plates may be readily removed and reversed so as to bring the opposite face thereof into contact with the gripping roller.

When the pulling machine is used in connection with the sewing machine it is essential that the feed rollers of the pulling machine shall move in unison and in timing with the feed of the sewing machine. It is preferred that this feeding movement of the puller shall be such as to exert a slight strain on the material passing through

the stitching mechanism. Whenever timing of the parts may be desired, it is essential that this timing shall be maintained. If the puller should get out of timing with the feed of the sewing mechanism and the material pulled while the needles are located thereon, then the needles would be bent or deflected. Again, if the puller wheels are slow or lag behind in their time of action, they will be of no assistance whatever in co-operating with the feed of the sewing machine in handling the fabric. For the above reasons it is absolutely necessary that the driving clutch and holding clutch for the puller shall be such that there is no lost motion in the parts, or failure on the part of the clutch members to grip the member co-operating therewith at the proper time. The above construction of clutch, which includes the hardened wear plate, accomplishes this result.

From the above construction it will be noted that I have provided a clutch wherein there are three equally spaced rollers. Therefore, when the clutch members are inserted in the sleeve these rollers with the springs which force the rollers outward on the hardened plates, will cause a self-centering of the clutch member in the sleeve. This self-centering of the clutch does away with any fine adjustment which might otherwise be necessary to bring the parts into proper co-operative relation.

It is obvious that minor changes in the details of construction and the arrangement of parts may be made without departing from the spirit of the invention, as set forth in the appended claims.

Having thus described my invention, what I claim is:

1. The combination of a sewing machine having a feeding mechanism and a puller machine located in rear of the sewing machine, said puller machine having a feeding member and means for operating the feeding member of the pulling machine, including a driving clutch and co-operating member, clutching devices located between the driving clutch and co-operating member, said clutching member having a hardened face on which the clutching devices rest.

2. The combination of a sewing machine having a feeding mechanism and a puller machine located in rear of the sewing machine, said puller machine having a feeding member and means for operating the feeding member of the pulling machine, including a driving clutch member, and a member co-operating therewith, clutching devices between the clutch member and the co-operating member, said clutch member having hardened plates on which the clutching devices rest.

3. The combination of a sewing machine having a feeding mechanism and a puller

machine located in rear of the sewing machine, said puller machine having a feeding member and means for operating the feeding member of the pulling machine, including a driving clutch member, and a member co-operating therewith, clutching devices between the clutch member and the co-operating member, said clutch member having hardened plates on which the clutching devices rest, and means for securing said wearing plates to the clutch members, whereby said plates may be removed and reversed.

4. The combination of a sewing machine having a feeding mechanism, of a pulling machine located in rear of the sewing machine, and having a feeding member, a shaft supporting the feeding member of the pulling machine, a shaft for operating the feeding mechanism of the sewing machine, and means for intermittently rotating the shaft of the pulling machine from the shaft of the sewing machine, including a sleeve fixed to the shaft of the pulling machine, a clutch member free on said shaft and extending into said sleeve, clutching rollers located between the clutch member and the sleeve, wear plates carried by said clutch member, on which said rollers rest, an arm rigidly attached to said clutch member, an eccentric on the shaft of the sewing machine, and means for oscillating said arm from said eccentric.

5. The combination of a sewing machine having a feeding mechanism, of a pulling machine located in rear of the sewing machine, and having a feeding member, a shaft supporting the feeding member of the pulling machine, a shaft for operating the feeding mechanism of the sewing machine, and means for intermittently rotating the shaft of the pulling machine from the shaft of the sewing machine, including a sleeve fixed to the shaft of the pulling machine, a clutch member free on said shaft and extending into said sleeve, clutching rollers located between the clutch member and the sleeve, wear plates carried by said clutch member, on which said rollers rest, an arm rigidly attached to said clutch member, an eccentric on the shaft of the sewing machine, means for oscillating said arm from said eccentric, and means for preventing the shaft of the puller from turning in the opposite direction, including a holding clutch member extending into said sleeve, clutching rollers between the holding member and the sleeve, wear plates carried by the holding member, on which the rollers rest, and means for preventing the holding member from turning with the shaft.

6. The combination of a sewing machine having a feeding mechanism, of a pulling machine located in rear of the sewing machine, and having a feeding member, a shaft supporting the feeding member of the pull-

ing machine, a shaft for operating the feeding mechanism of the sewing machine, and means for intermittently rotating the shaft of the pulling machine from the shaft of the 5 sewing machine, including a sleeve fixed to the shaft of the pulling machine, a clutch member free on the shaft and extending into said sleeve, hardened plates fixed to the clutch member within the sleeve, rollers 10 resting on the hardened plates and adapted to grip the sleeve, springs normally pressing the rollers into contact with the sleeve, an arm carried by the clutch member, an eccentric on the main shaft of the sewing 15 machine, and means for connecting said arm to said eccentric, whereby said arm is oscillated therefrom.

7. The combination of a sewing machine having a feeding mechanism, of a pulling 20 machine located in rear of the sewing machine, and having a feeding member, a shaft supporting the feeding member of the pulling machine, a shaft for operating the feeding mechanism of the sewing machine, and 25 means for intermittently rotating the shaft of the pulling machine from the shaft of the sewing machine, including a sleeve fixed to the shaft of the pulling machine, a clutch

member free on the shaft and extending into said sleeve, hardened plates fixed to the clutch member within the sleeve, rollers resting on the hardened plates and adapted to grip the sleeve, springs normally pressing the rollers into contact with the sleeve, an arm carried by the clutch member, an eccentric on the main shaft of the sewing machine, means for connecting said arm to said eccentric, whereby said arm is oscillated therefrom, and means for preventing said shaft of the puller from turning in 40 the opposite direction, including a holding clutch member extending into said sleeve, hardened plates carried thereby within the sleeve, rollers resting on said plates, and adapted to grip said sleeve, springs for 45 forcing said rollers upwardly on the plates into contact with the sleeve, and means for preventing said holding member from rotating.

In testimony whereof, I affix my signature, in the presence of two witnesses.

DUDLEY S. SEYMOUR.
